UNITED STATES PATENT OFFICE.

FRIEDRICH GEISSLER, OF DRESDEN, SAXONY, GERMANY, ASSIGNOR TO
FREDERICK SIEMENS, OF SAME PLACE.

GAS-REGULATOR.

SPECIFICATION forming part of Letters Patent No. 309,041, dated December 9, 1884.

Application filed March 26, 1884. (No model.) Patented in Germany March 25, 1883, No. 25,487.

To all whom it may concern:

Be it known that I, FRIEDRICH GEISSLER, a citizen of Saxony, residing at Dresden, in the Empire of Germany, have invented certain 5 new and useful Improvements in Gas-Regulators, of which the following is a specification.

My invention relates to that class of lamps for which Letters Patent of the United States were granted to Frederick Siemens on the 9th 10 day of January, in the year 1883, in which the heat of the products of combustion from the flame is imparted to the air-supply, or to the combustible gas, or to both, for the purpose of increasing the illuminating power of the 15 flame, by causing such products of combustion and air or gas to pass in opposite directions through adjacent regenerative chambers or passages. In lamps of this class an annular burner has its central space formed into 20 a regenerative chamber or passage, which communicates at its bottom with a passage or pipe leading to a chimney, and is extended upward at its top beyond the level of the burner, and provided with guiding-surfaces, 25 whereby the flame is spread out to a considerable width. This inner chamber serves for the downward passage of the products of combustion, which pass into it from the top of the flame, and are drawn downward through it 30 by the draft of the chimney, into which the products of combustion escape after imparting a part of their heat to the sides of the chamber. Surrounding the outside of the burner is a second chamber, open at its upper 35 and lower ends, which becomes heated by conduction and radiation from the heat given off to the central chamber, and imparts such heat to the air passing upward through the chamber on its way to the flame. On the upper 40 end of the inner chamber, which terminates at a moderate height above the burner, is fitted a separate cylinder composed of any suitable refractory material, which may be renewed or replaced with facility.

It has been observed that when lamps of this description are cold they burn but a small quantity of gas which is free from soot, and it is therefore necessary on first igniting to turn the cut-off cock in such a manner as to allow 50 a small quantity of gas to flow to the burner, and it is only by degrees that the continually-

increasing heating of the burner will allow of a corresponding increased gas-feed.

It is the object of my present invention to effect automatically a single continuous and 55 complete opening of the cut-off cock or register corresponding to the maximum requirements of the burner, and to operate automatically the continually - increasing gas-feed in such a manner as to correspond to every degree of heat of the burner.

Gas-burners have been heretofore described in which a rod of brass or other highly-expansible metal is placed within a gas-conducting tube, which is exposed to the products of 65 combustion and flame from the burner for the purpose of increasing the flow of gas as the parts become heated. According to my invention, however, the expansible rod is so arranged as to be directly exposed to the escaping products of combustion, and the wall of 70 the flue for the products of combustion is so constructed that its expansion assists the rod to operate the valve which governs the flow of gas. Some means should be provided for adjusting the length of the rod—as, for instance, 75 a screw.

In the accompanying drawings, Figure 1 is a vertical section on the line Z Z of Fig. 2. Fig. 2 shows a section on the line X X of Fig. 80 1. Fig. 3 is a section on the line Y Y of Fig. 1, and Fig. 4 is a section on the line W W of Fig. 1.

The gas is introduced through the pipe R into a chamber, G, terminating at the top in 85 an annular space, on which are fixed the small tubes C, forming the annular gas-burner, the gas issuing from which enters into combustion with the heated air passing up through the air-chamber or regenerator F. The air for combustion enters at the bottom of the annular chamber or regenerator F, and passing up through the latter, issues at the top in contact with the gas issuing from the tubes C, and enters into combustion therewith.

On the top of the central flue, S, is fitted a separate cylinder, I, and ring I', of suitable refractory material, which determine the breadth and height of the flame. The downward draft of the central flue, S, causes the combustion-gases to be drawn inward over the upper surface of the cylinder and down through the flue

S, whence they escape to the chimney through the passage B.

On the outside of the air-chamber F a second annular air-chamber, M, is provided, open 5 at the bottom, for the entrance of air.

The rod D, which should be constructed of some metal which is a good conductor of heat, is combined, as is clearly shown in Fig. 1, with the part of the burner N which is exposed to 10 the heat, and which extends downward from the passage B. The seat of the regulating device, in this case a simple hinge-valve, K, is at or near the end of the gas-feed pipe, which is connected to the part of the lamp E. The upper end of the rod D is provided with a regulating-screw, A, by means of which the position of the rod may be accurately adjusted. When the lamp is cold, the valve K lets just so 15 much gas through as the burner can completely consume when at that temperature. With the increasing heat and consequent increased elongation of the depressed part N of the lamp, as well as of the rod D, the valve K is correspondingly opened, and the gas-feed thereby 20 correspondingly increased. When the burner is extinguished, the valve K, the rod D, and the part N of the lamp return to their original 25 positions.

I am aware that it is not new to apply the 30 expansive and contracting power of a metallic rod to open and close a damper which governs the admission of air into a stove or other structure; but my invention differs from devices of this kind, as its object is not to reduce the 35 amount of air required to support combustion as the heat thereof increases, but to gradually increase the amount of gas required for illumination as the heat of combustion increases.

Instead of the hinge-valve K, illustrated in

Fig. 1, any other suitable device which will 40 effect the same purpose may be substituted.

Although I have selected a so-called "regenerative" lamp in this instance for the purpose of describing and illustrating the application of my invention, it is obvious that the principle 45 may be applied to other lamps and structures which have been and may hereafter be used.

I therefore claim and desire to secure by Letters Patent of the United States—

1. In a gas-lamp, the combination of an expansive and contractive part exposed directly to the escaping products of combustion, with a device normally open for increasing the supply of gas as the parts of the lamp become heated, substantially as described. 50

2. In a gas-lamp, the combination of a valve normally open, which regulates the amount of gas admitted to the burner, with a metallic rod exposed directly to the heat of the escaping products of combustion for operating said valve, 60 to increase the supply of gas as the parts become heated, as and for the purpose described.

3. The combination of the walls of the flue, through which the products of combustion escape from the lamp, a gas-regulating valve 65 normally open, and a metallic rod attached to said wall and operated by the expansion thereof, to cause the opening of the valve to receive the supply of gas as the parts become heated, substantially as described. 70

In testimony whereof I affix my signature in presence of two witnesses.

FRIEDRICH GEISSLER.

Witnesses:

C. MAX HERRMANN,
PAUL DUCKMÜLLER,

Both of Dresden.
